UNITED STATES PATENT OFFICE.

ORA A. COLBY, OF IRWIN, PENNSYLVANIA, ASSIGNOR TO WESTINGHOUSE ELECTRIC & MANUFACTURING COMPANY, A CORPORATION OF PENNSYLVANIA.

DOUBLE-HOT-CHAMBER FURNACE.

1,347,896.

Specification of Letters Patent. Patented July 27, 1920.

Application filed December 14, 1918. Serial No. 266,713.

To all whom it may concern:

Be it known that I, ORA A. COLBY, a citizen of the United States, and a resident of Irwin, in the county of Westmoreland and 5 State of Pennsylvania, have invented a new and useful Improvement in Double-Hot-Chamber Furnaces, of which the following is a specification.

My invention relates to electric furnaces 10 and particularly to high-temperature electric-resistance furnaces for heating and treating metals that may be operated continuously for comparatively long periods of time.

One object of my invention is to provide 15 a high-temperature electric-resistance furnace that will have several associated heating chambers so arranged as to require a minimum number of parallel-connected resistors to generate the necessary heat. Another object is to obtain a high thermal efficiency with a small furnace of this type.

Another object of my invention is to provide 20 an arrangement that will bring the connections between the metal-terminal connectors and the carbon electrodes at a distance from the heating chambers and that will allow of covering the connections with finely divided granular material to prevent 30 the air from coming into contact with the joint between the two materials.

In a copending patent application of F. Thornton, Jr., and O. A. Colby, Serial No. 198,275, filed Oct. 24, 1917, is shown and described 35 an electric-resistance furnace having a single heating chamber and a pre-heating chamber, the top and bottom walls of the heating chamber being made of blocks of carbonaceous material that constitute the resistors of the furnace. One feature of my invention consists in so locating an additional heating chamber as to require an increase of only 50% in the total energy input to the furnace. The additional heating chamber will materially increase the work output of such a furnace and this increase may approximate 100%.

The thermal efficiency of this type of furnace depends mainly upon the ratio of the 50 energy input to the radiating surface. By increasing the energy input in the double hot-chamber furnace without materially increasing the radiating surface, the thermal efficiency will be increased.

When the carbon electrodes, to which the

metal terminal plates in this type of furnace are attached, are located close to the heating chamber, they may become heated to such a high temperature as to cause the surface of the electrodes to oxidize and 60 crumble away. Such action will result in poor contact between the metal plate and the electrode and, if such heating is long continued, arcing may take place between the two, causing a still further deterioration 65 in the quality of the contact. By locating these electrodes and the joints substantially away from the furnace chamber proper, the temperature rise will be kept down and, by covering them with finely divided granular material, the oxidation will, to a great 70 extent, be prevented.

The above and other objects and the novel features of the invention will be apparent 75 from the following description taken in connection with the accompanying drawing that forms a part of this application and in which Figure 1 is a vertical, transverse, sectional view of an electric-resistance furnace embodying my invention; Fig. 2 is a sectional view of the furnace shown in Fig. 1 taken on the line II-II of Fig. 1, and Fig. 3 is a front view of a furnace embodying my invention.

Referring to Figs. 1 and 2, the furnace 80 construction comprises a suitable iron frame work and exterior shell 10 that carries the vertical walls 11 and bottom wall 12 of refractory material, the latter supporting a refractory-brick base structure 13. 90 A center wall 14 is spaced from the side walls 11 to form hoppers 15 into which granular material, such as graphite or coke, may be charged for a purpose to be described. The hoppers 15 extend downwardly into the furnace structure and in each of them is a solid terminal electrode 16 for leading current to the resistors. The electrodes 16 are located at the outer sides of the hoppers 15 near the bottom ends 95 thereof and rest on extensions 17 of the same material that are connected, at their outer ends, to metal terminal plates 18. The terminal plates 18 extend downwardly through the floors of boxes 19 that are attached to each side of the frame 10 and form terminals to which the supply mains are connected. The boxes 19 have bottom walls 20 composed of blocks of refractory material supported by a metal casing 21. 110

Masses of granular material 22, consisting of fine sand or silica, are employed to cover the joints between the metal terminal plates 18 and the electrode extension 17, thus preventing the air from coming into contact with, and deteriorating, the joint between the two members.

The main heating chambers 23 of the furnace are open at one end and otherwise 10 closed by top and bottom walls 24, 25 and 26 separated by spacers 27 that form the side walls of the heating chambers. The walls 24, 25 and 26 consist of carbonaceous materials such as silicon-carbid bricks or 15 slabs, and the intermediate spacers 27 may also consist of such blocks but any highly refractory material will serve the purpose, since it is not necessary that these spacers be of electrical conducting material.

20 The walls 24, 25 and 26 constitute the resistors of the furnace that are spaced from the terminal electrodes 16. The spaces between the electrodes and the resistors are filled with masses 28 of granular graphite or 25 coke packed to provide a medium between the electrodes and the resistors that is an electrical conductor and also a thermal insulator that is of greater cross section than the resistor to prevent overheating and consumption of the expensive electrodes 16.

30 The masses 28 oxidize and are gradually consumed and may be replaced by additional material introduced and tamped into the upper ends of the hoppers 15.

35 The wall 25 forms the floor of the upper heating chamber and the top wall of the lower heating chamber. A space 29 is provided above the resistor 24 and a similar space 30 is provided below the resistor 26 to 40 more effectively insulate the two heating chambers from the top and the bottom surfaces of the furnace. These air spaces serve to retard leakage of heat from the resistor blocks 24 and 26 and, since the resistance of 45 carbonundum changes slowly at high temperatures, the three sets of blocks constituting the top and bottom walls of the two chambers, after a few hours' run and heat interchange, will have approximately the same resistance and, eventually, will have 50 approximately the same temperature. Spacers 31 form the side walls of the spaces 29 and 30 and these may consist of small blocks of carbonaceous material but any highly refractory material will serve the purpose.

55 Within the fire-brick base 13 is inclosed a preheating chamber 32 underneath the lower of the two heating chambers 23 and separated from the latter by the air space 30 and a layer of the refractory material 13. The preheating chamber 32 is thus so located 60 that it will derive heat from the wall 26, which loses part of its heat through the air space 30 and the one layer of the refractory material 13. Cold articles, such as cold

pieces of metal, would be damaged if introduced directly into the high-temperature heating chambers 23 and they are, therefore, first heated to a moderately high temperature in the preheating chamber 32, after 70 which they may be introduced into either of the high-temperature chambers 23.

Temperatures up to about 1200° C. may be obtained in this furnace without difficulty, and the furnace is adapted to be used 75 with success for hardening tools and dies and for firing porcelain. A non-oxidizing atmosphere may be obtained within the furnace by spreading granular charcoal or carbon over the floors 25 and 26 near the doors 80 where it is burned by the entering air.

While I have shown and described my invention in detail, it is understood that numerous changes and adaptations may be made without departing from the spirit of 85 my invention and I desire, therefore, that only such limitations shall be imposed as are imposed by the prior art or are indicated in the appended claims.

I claim as my invention: 90

1. In an electric furnace, the combination with two associated heating chambers, of a preheating chamber and resistors for supplying heat to all of said chambers.

2. In an electric furnace, the combination 95 with two associated heating chambers and a preheating chamber, all in vertical alignment, of resistors for supplying heat to all of said chambers.

3. An electric furnace comprising two 100 heating chambers and a preheating chamber in vertical alignment, and resistors for supplying heat to all of said chambers, one of the said resistors constituting the floor of the upper chamber and the top wall of the 105 lower heating chamber.

4. An electric furnace comprising two heating chambers and a preheating chamber in vertical alignment, said heating chambers having top and bottom walls formed of 110 blocks of refractory electrical-conducting material constituting the resistors of the furnace, the bottom wall of the upper heating chamber forming the top wall of the lower heating chamber. 115

5. An electric furnace comprising two heating chambers and a preheating chamber in vertical alignment and resistors disposed to form the top and bottom walls of both of 120 said heating chambers and blocks of refractory material for separating the top and bottom walls of said heating chambers.

6. In an electric furnace, the combination with two superposed heating chambers, of resistors adjacent the same comprising solid 125 blocks of refractory electrical conducting material in contact with one another and forming the top and bottom walls of said chambers, terminal electrodes, and a mass of thermal-insulating and electrical-conducting 130

granular material interposed between each of the electrodes and the ends of the resistor to prevent overheating of the electrodes.

7. In an electric furnace, the combination with two superposed heating chambers, and a preheating chamber, of resistors comprising solid blocks of refractory electrical-conducting material in contact with one another and forming certain walls of said chambers, 10 hoppers on opposite sides of said chambers, terminal electrodes in said hoppers, and a mass of thermal-insulating and electrical-conducting material between each of said electrodes and the resistors and of greater 15 cross-section than the resistor to prevent overheating of the electrodes.

8. In an electric furnace, the combination with two superposed heating chambers having walls formed of blocks of refractory 20 electrical-conducting material constituting the resistors of said furnace, and a preheating chamber, of hoppers on opposite sides of said chambers, solid carbonaceous terminal electrodes in said hoppers, and a mass of 25 thermal-insulating and electrical-conducting material between each of said electrodes and the resistors, said masses of material being granular and of greater cross section than the resistor to prevent overheating and 30 consumption of the electrodes.

9. An electric furnace comprising two superposed heating chambers each having an open end, top and bottom walls formed of solid refractory electrical-conducting material that constitute the resistors of the furnace, and side walls of refractory material for separating the top and bottom walls.

10. An electric furnace comprising two superposed heating chambers having top 40 and bottom walls formed of blocks of refractory electrical-conducting material constituting the resistors of the furnace.

11. An electric furnace comprising resistors consisting of blocks of electrical-conducting refractory material inclosing 45 two associated spaces which constitute the heating chambers of the furnace, terminal electrodes, and a mass of thermal-insulating and electrical-conducting material between each of said electrodes and said resistor, said masses of conducting material being granular and of greater cross-section than the resistor to prevent overheating and consumption of said electrodes.

55 12. An electric heating furnace comprising two superposed heating chambers, a preheating chamber, and a resistor between said preheating chamber and one of said heating chambers and arranged to supply more heat to said heating chamber than to said preheating chamber.

13. An electric heating furnace comprising two heating chambers and a preheating chamber in vertical alinement, and resistors, 60 one part whereof is disposed between said

preheating chamber and one of said heating chambers and closer to the heating chamber than to the preheating chamber so as to supply more heat to the former than to the latter.

70 14. An electric furnace comprising two heating chambers and a preheating chamber in vertical alinement, and resistors having one part disposed between said heating chamber and said preheating chamber and constituting a wall for the heating chamber, and a layer of material for separating said heating chamber from said preheating chamber.

15. An electric furnace comprising two heating chambers and a preheating chamber in vertical alinement, resistors having one part disposed between said heating chamber and said preheating chamber and constituting a wall of said heating chamber, a layer of material for separating said heating chamber from said preheating chamber, terminal 90 electrodes on opposite sides of said chambers, and a mass of electrical conducting material between each electrode and said resistors.

95 16. An electric furnace comprising two heating chambers and a preheating chamber in vertical alinement, resistors having one part constituting the floor of the upper heating chamber and the top of the lower heating chamber, another part constituting the floor of the lower heating chamber, a layer of material of low thermal and electrical conductivity between said lower resistor and said preheating chamber, hoppers at opposite sides of said resistors, terminal 105 electrodes in said hoppers, and a mass of electrical - conducting thermal - insulating granular material between each electrode and the resistor adapted to prevent overheating of said electrodes.

110 17. An electric furnace comprising two heating chambers and a preheating chamber in vertical alinement, resistors for supplying heat to all of said chambers, hoppers on opposite sides of said chambers, terminal electrodes in said hoppers, lateral projections on said electrodes for connecting to terminal connectors, and masses of granular material for covering the end portions of each of said lateral extensions.

115 18. In an electric furnace, the combination with a heating chamber, a preheating chamber and resistors for supplying heat to all of said chambers, of means for reducing the amount of heat conducted away 120 from said resistors and said chambers.

19. In an electric furnace, the combination with two heating chambers, a preheating chamber, and resistors for supplying heat to all of said chambers, said chambers 130

and resistors being in vertical alinement, of jacketing means in alinement with said chambers and said resistors for reducing the amount of heat conducted away from 5 said resistors and said chambers.

20. In an electric furnace, the combination with two heating chambers and a pre-heating chamber in vertical alinement, said heating chambers having top and bottom 10 walls formed of blocks of refractory elec-

trical-conducting material constituting the resistors of the furnace, of jacketing means located above said heating chambers and below said preheating chamber for reducing the amount of heat conducted away from 15 said resistors and said chambers.

In testimony whereof I have hereunto subscribed my name this 30th day of Nov., 1918.

ORA A. COLBY.
